15 Claims. (Cl. 242—56.6)

This invention relates to apparatus for cutting and coiling slit paper webs and more particularly to apparatus for cutting transversely longitudinally slit paper webs and coiling the several webs thereby created.

Machines for slitting a web of paper longitudinally into a plurality of webs are of numerous designs and are quite old in the art. However, devices for rewinding or coiling of the slit webs have been limited in their ability to automatically start each individual slit web onto separate reel cores mounted side by side on a mandrel.

An object of this invention is to cut transversely a web of paper having a plurality of longitudinally spaced slits, thereby creating a plurality of paper webs.

Another object of this invention is to automatically start a plurality of paper webs to wind onto separate reel cores.

A further object of this invention is to overdrive a plurality of paper webs onto separate reel cores to form convolutions tightly around said reel cores.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a schematic end elevation view of the apparatus embodying the invention attached to a slitting machine.

Fig. 2 is a schematic front elevation view of the apparatus embodying the invention attached to a slitting machine with portions of the front cover plate broken away.

Fig. 3 is a left end elevation of the carriage unit with the side cover plate removed and portions of the pinion confining plates and drive roller broken away.

Fig. 4 is an exploded isometric view of the mechanism for driving the resilient rollers.

Fig. 5 is a detail view of the latch member for holding the carriage in a locked position.

Fig. 6 is a partial plan view of the knife guard retracting mechanism viewed from underneath the top cover plate.

Fig. 7 is an isolated end elevation view of the drive roller and tension return spring.

Fig. 8a is a diagrammatic view of the carriage unit in a position ahead of the proper position for transversely cutting a slit web. In this position the web is cut prior to the carriage reaching the end of its travel.

Fig. 8b is a diagrammatic view of the carriage unit in the proper position for cutting a web transversely at the time the carriage reaches the end of its travel.

Fig. 8c is a diagrammatic view of the carriage unit in a position behind the proper position for transversely cutting a slit web. In this position the carriage reaches the end of its travel before the web is cut.

Fig. 9 is a detail view taken along the line 9—9 in Fig. 6 of mounting for cam follower and link assembly.

2

A machine for slitting a web of paper longitudinally into a plurality of paper webs is generally designated by the reference numeral 1. An apparatus for cutting transversely the longitudinally slit paper web and coiling the several paper webs created onto individual reel cores is generally designated by the reference numeral 2 (Figs. 1 and 2).

Referring to Figs. 1 and 2, the web 3 is fed from a supply roll 4 controlled by a power source such as an electric motor 5 through a suitable pulley or gear drive arrangement and around a series of rollers 6 which insures proper feeding of the web. As the web passes over a roller 7, it passes between a series of longitudinally spaced rotary slitters 8 and rotary knives 9 which cooperate with each other to slit the web 3 into predetermined widths. The slitters 8 are movable into a position for slitting from a nonoperative or neutral position by means of a series of handles 10.

The web 3 continues past the slitters 8 and knives 9 and partially around a drive roller 11 which coacts with rollers 12 and 13 to wind the slit web around a plurality of reel cores 14.

In order to wind the slit web around the reel cores 14, it is necessary to start the web 3 in some manner to wrap around the cores. Several methods not within the scope of the invention are available to perform this operation. One method would be to tape the web onto the reel cores, while another method would be to groove the reel cores transversely and tuck the web into the groove. Aside from the fact that these methods are laborious, they would not be suitable where it is desired to automatically splice one end of a reel of webbing onto another, since the ends of the webbing on the reel cores would require treatment to prepare them for splicing such as removal of the tape or trimming of that portion of webbing creased by tucking it into the groove of the reel cores. Either of the methods is adapted to start the webbing to wrap around the reel cores with the slits extending close to the edge of the web, leaving the several webs connected or extending through the edge leaving the several webs disconnected.

The apparatus designated by the reference numeral 2 (Fig. 2) is attached to the slitting machine 1 by two sets of U bolts 15 which clamp around a bar 16 supporting the slitter assembly and are attached by lock nuts 17 or other suitable fastening means to angle irons 18 carried on each end of the apparatus 2. The angle iron plates 18 are fastened by bolts and nuts (not shown) to support bars 19 which are rigidly attached to irregularly shaped plates 20 supporting longitudinally spaced fixed parallel racks 21. The racks 21 are adapted to support and carry a carriage unit 22 therebetween. The carriage unit 22, being movable on the racks 21 toward and away from the machine 1, has a top cover plate 23, a front plate 24, a pair of side plates 25 and a pair of end covers 26. On each end of the carriage unit (Figs. 1 and 3) there is a pinion gear 27 fixedly mounted on a rotatable shaft 28 journaled in the side plates 25 and adapted to engage the racks 21. A pair of plates 29 fixed to each side of the racks 21 confines the pinions 27 as they move along the racks.

The carriage unit 22 is supported by the racks 21 and by a pair of rollers 30 rotatably mounted on parallel shafts 31 fixed to an angular bracket 32 attached to the top cover plate 23 of the carriage unit. The rollers 30 maintain the pinions 27 engaged with the racks 21 and prevent oscillatory movement of the carriage 22. The carriage unit 22 is normally held away from the machine 1 by a carriage return spring 33 (Fig. 6). The carriage return spring 33 is a torsion spring which fits over the shaft 28 and is attached on one end to the sleeve 34 of the pinion gear 27 and on the other end to a bracket

35 supported by the top cover plate 23 and depending therefrom.

A knife 36 for cutting the web transversely is supported by the top cover plate 23 and is attached thereto by means of a plurality of screws 37 or other suitable fastening means and is disposed to extend outwardly from the carriage toward the machine 1. The knife 36 consists of a series of V-shaped teeth curved upwardly to give good angle of penetration into the web and to prevent the teeth from striking the reel cores 14. A retractible guard 38 lies over the knife for protection of the machine operator as well as providing a rounded edge to facilitate pulling the webbing taut prior to moving the carriage unit 22 toward the machine 1. The knife guard 38 cannot be retracted unless the carriage is moved toward the machine 1 since the mechanism for retracting the knife guard which is to be described hereinafter is designed to prevent it from doing so.

The mechanism for retracting the knife guard 38 comprises a cam means 39 carried by the shaft 28 and capable of being rotated by the shaft 28, a cam follower 40 connected to a link 41 and disposed to follow a cam 42, and other linkage 43 connected to the link 41 and knife guard 38. The linkage 43 is constructed to lie slightly over center of the pivot points 48a and 54a when the carriage unit is furthest away from the machine 1 so that the knife guard cannot be retracted by pushing against it. As the carriage unit is moved toward the machine 1, the cam 42 being rotated by the shaft 28 pivots the cam follower 40 about its center of support 46. The linkage 43 which is moved as the cam follower 40 is pivoted passes from over center to and through center and continues to move away from center thereby retracting the knife guard 38. However, retraction of the knife guard 38 does not take place until the carriage unit is very close to the end of its travel.

The cam means 39 consists of a bushing 44 fixed to the shaft 28. The bushing 44 has a threaded male portion adapted to screw into the threaded female portion of a bushing 45 journaled on said shaft 28 and located thereon to receive the male member. The end of the bushing 45 opposite the female portion has the cam surface 42 with quite a sharp rise. The sharp rise of the cam surface 42 bears against the cam follower 40 to hold the bushing 45 while the male portion is screwing into the female portion and then when the connection between the male portion and female portion is tight, the cam surface 42 is compelled to rotate as the carriage continues forward.

The cam follower 40 disposed to follow the cam surface 42 is rigidly attached to the link 41, thereby becoming integral therewith. The link 41 and cam follower 40 are pivotally mounted on a pin 46 fixed to the top cover plate 23 and extending downward into a bracket 47 attached to the front cover plate 22 of the carriage unit. The other end of the link 41 is pivotally mounted on a pin 48 fixed to a link 49 intermediate of its ends. The link 49 adapted to move laterally is normally restrained by a spring 50 attached on one end to a pin 51 fixedly depending from the top cover plate 23 and on its other end to the link 49; hence the cam follower 40 is caused to follow the cam surface 42 by action of the spring 50 through the links 41 and 49.

Another link 52 pivotally mounted on one end to a pin 53 fixed to the knife guard is also pivotally mounted on its other end to the pin 48. A pin 54 fixed to the other end of the link 49 pivotally carries a link 55 and a link 56. The other end of link 56 is pivotally mounted on a pin 57 fixed to the top cover plate while the other end of the link 55 is pivotally mounted on a pin 58 fixed to the knife guard. The knife guard 38 is provided with a plurality of slots 59 suitably spaced from each other along its length. The slots 59 guide the movement of the knife guard by following the pins 60 fixed to the top

cover plate. The top cover plate 23 is provided with slots 61 to permit movement of the pins 53 and 58.

The male portion of the bushing 44 screws into the female portion of bushing 45 until a tight connection is made. As the cam surface 42 rotates, it causes the cam follower 40 and link 41 to pivot around the pin 46. As the link 41 pivots, it carries the link 49 laterally against the tension of the spring 50. The lateral movement of the link 49 causes the link 52 and the link 55 to pivot and to move longitudinally, thus retracting the guard. When the carriage returns to its starting position by action of the carriage return spring 33, the knife guard 38 is moved back into position to cover the knife 36 by action of the linkage 43 moved by the spring 50 in co-operation with the cam means 39. The cam means 39 is rotated by the shaft 28 inasmuch as the connection between the bushings 44 and 45 is still tight; however, a shoulder 62 on the bushing 45 strikes the top cover plate 23 (on the return but not on the forward movement of the carriage unit since the carriage reaches the end of its forward travel before the shoulder 62 strikes the cover plate 23), therefore breaking the tight connection between the bushings and holding the bushing 45 stationary as the male portion of the bushing 44 screws out.

The web of paper 3 is cut by the knife teeth first penetrating the paper by piercing it and then continuing to penetrate the paper to shear it. The cutting action takes place when the paper web 3 is tautly wrapping around the reel cores 14 and the web 3 is held securely on the top cover plate 23 and over the knife edge 36. Hence, the place where cutting occurs depends upon two factors, one being the position of the carriage 22 from the machine 1 at the start of its travel and the other being the amount of webbing (Figs. 8a, 8b and 8c) from the bottom of the reel cores 14 to the carriage. However, if the webbing is pulled tautly over the top cover plate 23 before the carriage unit 22 begins its travel, the variable factor of the amount of webbing from the reel cores 14 to the carriage unit 22 is eliminated, since that distance will then always be equal to the distance that the carriage 22 is from the machine 1.

The racks 21 are fixed with respect to the machine 1 so that when the carriage 22 reaches the end of its travel on the racks, the knife blade 36 will lie very near the nip point or the point of contact between the roller 11 and the reel cores 14. Hence, the best place for cutting to occur would be at the time the carriage is at the end of its travel, since then the paper webs would be close to the nip point. If the distance of the carriage from the machine is such that the carriage reaches the end of its travel before the web wraps tautly around the periphery of the reel cores, the web will not be cut. Moreover, if the distance of the carriage from the machine 1 is such that the carriage does not reach the end of its travel at the time the web wraps tautly around the periphery of the reel cores, the web will be cut prior to the carriage reaching the end of its travel. Accordingly, the distance of the carriage 22 from the machine 1 at the start of its travel should be such that the carriage reaches the end of its travel at the time the web wraps tautly around the periphery of the reel cores 14. The movement of the carriage unit 22 away from the machine 1 is limited by a stop 63 (Fig. 1), while movement of the carriage toward machine 1 is limited by a rubber drive wheel 64 carried by the carriage unit contacting the roller 11.

It would not be sufficient merely to cut the paper web transversely but it is necessary to hold the webs 3 against the reel cores until they are nipped between the reel cores 14 and the roller 11. In fact, it would be desirable not only to hold the webs 3 against the reel cores 14 but to positively drive the webbing into the nip point.

A shaft 65 mounted on carriage 22 parallel to the shaft 66 or mandrel carrying the reel cores 14 (Figs. 1, 2 and 75 4) has a plurality of soft rubber rollers 67 loosely jour-

naled thereon. There is a separate rubber roller to correspond to each individual reel core. However, it would be possible to have a single rubber roller in place of the several rubber rollers without departing from the spirit of the invention. Since it is possible that the slack of each slit web may vary, it is desirable to have individual rollers to drive the webs. The rubber rollers 67 are disposed to hold the webs against the reel cores 14 when the carriage unit 22 has reached the end of its travel and upon receiving power through a drive train 68 (Figs. 3 and 4) from the roller 11, drive the webs into the nip point. The rubber wheel 64 rotatably mounted on a shaft 69 fixed to a plate 70 attached to the end plate 25 is disposed to come into contact with the roller 11 when the carriage 22 is at the end of its travel on the racks 21.

A gear 71 also rotatably mounted on the shaft 69 is drivably connected to the wheel 64 by a pawl 72 pivotally mounted on a pin 73 fixed in said wheel. In Fig. 7 a spring 74, connected on one end to a stud pin 75 fixed to the wheel 64 and on its other end to a pin 76 attached to an arm 77 fixed to the pin 73 or integral therewith urges the pawl 72 (Fig. 4) into engagement with the gear 71. The gear 71 meshes with a smaller gear 78 rotatably mounted on a pin 79 fixed to a strap 80 adjustably connected to the side plate 25. The gear 78 meshes with a still smaller gear 81 rotatably mounted on a pin 82 fixed to a plate 83 and passing through the side plate 25. The gear 81 is integral with or attached to a larger concentrically mounted gear 84 which meshes with a small gear 85 fixed to the shaft 65. The shaft 65 journaled on one end in the plate 83 extends the length of the carriage unit 22 and is journaled on its other end in a plate identical to the plate 83. The plate 83 has an arcuate slot 86 to permit adjustment of the rollers 67 with respect to the reel cores 14. A bolt 87, passing through the arcuate slot 86, supports the plate 83 to the side plate 25. A cut-out portion 88 in the side plate 25 permits easy removal of shaft 65 with attendant mountings. An identical wheel, gear train and support plates are found on the other side of the carriage unit.

As the carriage unit 22 reaches the end of its travel on the racks 21, it is held from returning to its starting position by a latch 89 (Figs. 3 and 5). The latch 89 is pivotally mounted on a pin 90 fixed in the sides of a U-shaped bracket 91 which is secured to the top cover plate 23. A compression spring 92 positioned between the latch 89 and the top cover plate 23 urges the latch upwardly against the rack 21. However, normally the shoulder portion 93 of the latch rides along the rack teeth as the carriage moves, but when the carriage reaches the end of its travel, a recessed portion 94 provided in the rack 21 permits the shoulder 93 to come into engagement therewith. Accordingly, with the spring 92 holding the shoulder 93 of the latch in the recess 94 and the carriage return spring 33 holding the latch 89 against the shoulder of the recess 94, the carriage unit 22 is held in a locked position. The carriage unit 22 is released from its locked position by a stud pin 95 (Fig. 4) fixed to the inner face of the wheel 64 and adapted to engage an ear 96 of a knock-off lever 97 (Fig. 3) which cams the latch 89 out of engagement with the rack 21. The knock-off lever 97 is pivotally mounted on a pin 98 fixed to the rack 21 and is normally held against a stop pin 99 fixed to the rack by a spring 100. The spring 100 is attached on one end to a projecting arm 101 of the lever 97 and on its other end to a pin 102 fixed to the rack. The stud pin 95 engages the ear 96 of the knock-off lever 97 to pivot it about the pin 98. The cam surface 103 on the knock-off lever 97 adapted to bear against the projecting arm 104 of the lock arm 89 moves the lock arm 89 about the pin 90 against the pressure of the spring 92 as the knock-off lever 97 pivots, thereby releasing the lock arm 89 from the rack 21 and allowing the carriage return

spring 33 to return the carriage unit 22 to its initial position against the stop 63.

To start the slitting operation, the paper web 3 is threaded from the supply roll 4 about the rollers 6 and then over the roller 7 down past the slitters 8 and knives 9, past the roller 11, between the roller 11 and reel cores 14, around the reel cores 14 and up over the top cover plate 23.

The slitters 8 are then engaged with the knives 9 by means of the handles 10 to slit the web 3 and the power is supplied to slowly feed the web 3 through the machine 1. The roller 11, the roller 12 and the roller 13 frictionally drive the reel cores 14. The web 3 is fed through the machine 1 until the start of the slit is in register with or slightly past the leading edge of the knife guard 38. Since the several webs created wind on the individual reel cores without interwinding, there is no objection to cut the slit webbing so that the several webs are disconnected from each other; however, it would be within the spirit of the invention to leave the several webs connected at their ends.

After the slits are in register with the leading edge of the knife guard 38, the machine 1 is stopped. The machine operator, then pulling the webbing 3 tautly over the top cover plate and holding the web 3 securely thereon, pushes the carriage unit 22 toward the machine 1 to the locked position. During this operation, the knife guard 38 retracts and the knife 36 cuts the paper web transversely, thereby creating a plurality of webs in the manner explained above. From Fig. 8a it can be seen that if the cutting action occurred before the carriage 22 reaches the end of its travel, it is possible that the paper webs would be too short to be held against the periphery of the reel cores by the soft rubber rollers 67 and consequently they would not be fed into the nip point.

The soft rubber rollers 67 actually may be compressed as they hold the webs 3 against the reel cores 14. The degree of pressure that they exert is adjustable by loosening the bolt 87 and moving the plate 83. The rubber rollers 67 are loosely mounted on the shaft 65 so that any slippage which would occur takes place between the rubber rollers 67 and the shaft 65, whereas if the rubber rollers were rigidly mounted on the shaft any slippage occurring would be between the rubber rollers and the paper winding around the reel cores and this action would damage the rubber rollers quite quickly.

The web 3 has been severed and the soft rubber rollers 67 are holding the several webs 3 against individual reel cores 14. The machine operator now turns on the power to start the machine 1. The wheel 64 being in contact with the roller 11 is frictionally driven by the roller 11 to drive the soft rubber rollers 67 through the gear train 68. The rollers 67 are in fact overdriven so that any slack occurring will be taken up as the webs are fed into the nip point. The wheel 64 turns through a predetermined number of degrees rotation and then the stud bolt 95 actuates the knock-off lever 97 to allow the carriage to be returned to its starting position by action of the carriage return spring 33.

Since the wheel 64 is rotatably mounted on the shaft 69 and is connected to the gear 71 by the pawl 72, it will be returned to its initial position prior to rotation by a torsion or clock spring 105 (Fig. 7) attached on one end to a pin 106 carried by the wheel and on its other end to the shaft 69. A pin, Fig. 4, 107 fixed to the plate 70 limits the return rotation of the wheel 64. Hence, the soft rubber rollers 67 are always driven the same amount each time.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention

tion, therefore, to be limited only as indicated by the scope of the following claims.

What is claimed is:

1. In an apparatus for cutting and coiling slit paper webs comprising a pair of rollers having parallel axes located at different levels, rotatable in opposite directions and disposed to form a bite, one of the rollers consisting of a plurality of identically shaped reel cores placed side by side, thereby providing separate cores for slit paper webs to be wound on each core, the other roller being unitary in construction, a pair of longitudinally spaced parallel racks extending rearwardly from a point proximate to the bite, the racks being fixed with respect to the roller of unitary construction, a carriage movable on said racks toward and away from said rollers, the length of carriage travel being of a distance so that the slit webs of paper to be cut which pass between the rollers, partially around the reel cores and over the carriage will be severed along a transverse axis and the cut edge remaining will be presented to the bite at the end of the carriage travel toward the rollers, a cutting device mounted on said carriage in a position to cut the slit webs along a transverse axis and to lie very near the bite point when the carriage reaches the end of its travel toward the rollers, a means for holding the transversely cut webs of paper against the periphery of the reel cores when the webs are presented to the bite, said holding means being capable of driving said webs into the bite and means for causing said holding means to drive said webs of paper into the bite.

2. In an apparatus for cutting and coiling slit paper webs comprising a pair of rollers having parallel axes located at different levels, rotatable in opposite directions and disposed to form a bite, one of the rollers being composed of a plurality of collocating sections, thereby providing separate cores for slit individual paper webs wound on each section, the other roller being unitary in construction, a pair of longitudinally spaced parallel racks extending rearwardly from a point proximate to the bite, the racks being fixed with respect to the roller of unitary construction, a carriage movable on said racks toward and away from said rollers, the length of carriage travel limited in the forward direction by said rollers and in the rearward direction by a stop position so that the slit webs of paper which pass between the rollers partially around the collocating sections and over the carriage will be severed along a transverse axis to become separate webs and the cut edge remaining will be presented to the bite at the end of the carriage travel toward the rollers, a means for cutting the slit webs along a transverse axis to become separate webs mounted on said carriage in a position so that it will lie very near the bite when the carriage reaches the end of its travel toward the rollers, a means carried by said carriage for holding the slit webs against the periphery of the collocating sections when the webs are presented to the bite, said holding means being capable of driving said webs into the bite, and a means operable for driving said holding means.

3. An apparatus for cutting and coiling slit paper webs comprising a pair of cooperating rollers rotatable in opposite directions and disposed to form a bite, one of the rollers being composed of two collocating sections, thereby providing separate cores for slit paper webs to be wound on each section, the other roller being unitary in construction, a pair of longitudinally spaced parallel racks extending rearwardly from a point proximate to the bite, the racks being fixed with respect to the roller of unitary construction, a carriage movable on said racks toward and away from said rollers, the length of carriage travel limited in the forward direction by a stop positioned so that the slit webs of paper which pass between the rollers partially around the collocating sections and over the carriage will be severed along a transverse axis to become separate webs and the cut

edge remaining will be presented to the bite at the end of the carriage travel toward the rollers, a cutting device mounted on said carriage in a position to cut the webs along a transverse axis and to lie very near the bite point when the carriage reaches the end of its travel toward the rollers, a shaft parallel to said rollers and journaled in said carriage carrying a resilient roller disposed to hold the slit webs against the periphery of the collocating sections when the webs are presented to the bite, the shaft, adapted to be driven, drives the resilient roller, thereby driving said webs into the bite, and a means operable for driving said shaft.

4. In an apparatus for cutting and coiling slit paper webs comprising a pair of rollers having parallel axes, disposed to form a bite and rotatable in opposite directions, one of the rollers consisting of a plurality of identically shaped reel cores placed side by side, the other roller being unitary in construction, a pair of longitudinally spaced parallel racks extending rearwardly from a point proximate to the bite, the racks being fixed with respect to the roller of unitary construction, a cutting means movable on said racks toward and away from said rollers, the length of travel being of a distance so that the slit paper webs passing between the rollers partially around the reel cores and over the cutting means will be severed along a transverse axis and the cut edge remaining will be presented to the bite at the end of the travel of the cutting means toward the rollers, a means for holding the transversely cut paper webs against the periphery of the reel cores when the webs are presented to the bite, said holding means being capable of driving said webs into the bite and means for causing said holding means to drive the webs into the bite.

5. An apparatus for cutting and coiling slit webs of paper comprising a pair of cooperating rollers rotatable in opposite directions and disposed to form a bite, one of the rollers being composed of two collocating sections, thereby providing separate cores for slit paper webs to be wound on each section, the other roller being unitary in construction, a pair of longitudinally spaced parallel racks extending rearwardly from a point proximate to the bite, the racks being fixed with respect to the roller of unitary construction, a carriage movable on said racks toward and away from said rollers, the length of carriage travel limited in the forward direction by a stop positioned so that the slit webs of paper which pass between the rollers partially around the collocating sections and over the carriage will be severed along a transverse axis to become separate webs and the cut edge remaining will be presented to the bite at the end of the carriage travel toward the rollers, a cutting device mounted on said carriage in a position to cut the webs along a transverse axis and to lie very near the bite point when the carriage reaches the end of its travel toward the rollers, a shaft parallel to said rollers and journaled in said carriage carrying resilient rollers spaced from each other along the shaft centrally opposite the collocating sections and disposed to hold the slit webs against the periphery of the collocating sections when the webs are presented to the bite, the shaft adapted to be driven frictionally drives the resilient rollers, thereby driving said webs into the bite, and a means operable for driving the said shaft.

6. In an apparatus for cutting and coiling a web of paper comprising a pair of rollers having parallel axes located at different levels, rotatable in opposite directions and disposed to form a bite, one of the rollers consisting of a plurality of identically shaped collocating reel cores, the other being unitary in construction, a pair of longitudinally spaced parallel racks extending rearwardly from a point proximate to the bite, the racks being fixed with respect to the roller of unitary construction, a carriage movably supported on said racks toward and away from said rollers, the length of carriage travel being of the

distance so that the web of paper to be cut which passes between the rollers partially around the reel cores and over the carriage will be severed along a transverse axis and the cut edge remaining will be presented to the bite at the end of the carriage travel toward the rollers, a cutting means having a plurality of upwardly curved V-shaped teeth mounted on said carriage in a position to cut the web along a transverse axis and to lie very near the bite point when the carriage reaches the end of its travel toward the rollers, a rotatable holding means for holding the transversely cut web of paper against the periphery of the reel cores when the web is presented to the bite, said holding means attached to said carriage being capable of driving said web into the bite, a means operable for driving said holding means, a latch pivotally mounted to one of said racks for holding the carriage in a fixed position when it reaches the end of its travel toward the roller, a means operable for unlatching the carriage from its latched position, and a means for returning the carriage to its position away from the rollers.

7. In an apparatus for cutting and coiling a web of paper comprising a pair of rollers having parallel axes located at different levels, rotatable in opposite directions and disposed to form a bite, a pair of longitudinally spaced parallel racks extending rearwardly from a point proximate to the bite, the racks being fixed with respect to one of said rollers, a cutting means movable on said racks toward and away from said rollers, the length of travel being of the distance so that the web of paper passing between the rollers partially around one of the rollers on over the cutting means will be severed along a transverse axis and the cut edge remaining will be presented to the bite at the end of the travel of the cutting means toward the rollers, a means carried by said cutting means for limiting movement of the cutting means toward the rollers by one of the rollers, a stop means carried by one of said racks for limiting movement of the cutting means away from said rollers, a means for constantly urging the cutting means away from said rollers, thereby normally holding said cutting means against the stop means, a latch means pivotally mounted on said cutting means and disposed to engage said racks to hold the cutting means in a fixed position when the cutting means has reached the end of its travel toward the rollers, a means carried with said cutting means for holding said web of paper against the periphery of one of said rollers when the web is presented to the bite, said holding means being capable of driving the web into the bite, a means operably carried by said cutting means for driving said holding means, said driving means receiving its driving power from one of said rollers and transmitting the power to the holding means to drive the web into the bite, a means operable for disengaging the latch means from said racks, and a means carried by said driving means for actuating the means to disengage the latch means from said racks after the web has been driven into the bite.

8. In an apparatus for cutting and coiling paper comprising a pair of rollers having parallel axes located at different levels, rotatable in opposite directions and disposed to form a bite, one of the rollers being composed of two collocating sections, thereby providing separate cores for slit paper webs to be wound on each section, the other roller being unitary in construction, a pair of longitudinally spaced parallel racks extending rearwardly from a point proximate to the bite, the racks being fixed with respect to the roller of unitary construction, a carriage movable on said racks toward and away from said rollers, the length of carriage travel being of a distance so that the slit paper webs passing between the rollers partially around the collocating sections and over the carriage will be severed along a transverse axis and the cut edge remaining will be presented to the bite at the end of travel of the carriage toward the rollers, a suitable means carried by said carriage for limiting movement of the carriage toward the rollers by the roller of unitary

construction, a stop means mounted on one of said racks for limiting movement of the carriage away from the rollers, a means for constantly urging the carriage away from said rollers thereby normally holding the carriage against the stop means, a cutting means mounted on said carriage in a position to cut the webs along a transverse axis and to be very near the bite point when the carriage reaches the end of its travel toward the rollers, a latch means pivotally mounted on said carriage and disposed to engage one of said racks to hold the carriage in a fixed position when the carriage has reached the end of its travel toward the rollers, a shaft parallel to said rollers journaled in said carriage and carrying resilient rollers spaced from each other along said shaft centrally opposite the collocating sections and disposed to hold the slit webs against the periphery of the collocating sections when the webs are presented to the bite, the shaft adapted to be driven drives the resilient rollers, thereby driving said webs into the bite, a means operable or driving said parallel shaft through a predetermined number of degrees rotation after the carriage has reached the end of its travel toward the rollers, a means pivotally mounted on one of the racks operable for disengaging the latch means from the rack and a means carried by said driving means for actuating the means for disengaging the latch means from the rack after the webs have been driven into the bite.

9. In an apparatus for cutting and coiling slit paper webs comprising a pair of rollers having parallel axes located at different levels, rotatable in opposite directions and disposed to form a bite, one of the rollers being composed of a plurality of collocating sections, thereby providing separate cores for slit paper webs to be wound on each section, the other roller being unitary in construction, a pair of longitudinally spaced externally supported parallel racks extending rearwardly from a point proximate to the bite, the racks being fixed with respect to the roller of unitary construction, a carriage supported by said racks and movable thereon toward and away from said rollers, the length of carriage travel being of a distance so that the slit paper webs passing between the rollers partially around the collocating sections and over the carriage will be severed along a transverse axis and the cut edge remaining will be presented to the bite at the end of travel of the carriage unit toward the rollers, a rotatable means carried by said carriage for limiting movement of the carriage toward the rollers by the roller of unitary construction, a stop means carried by one of said racks for limiting movement of the carriage away from the rollers, a means for constantly urging the carriage away from said rollers, thereby normally holding the carriage against the stop means, a cutting means mounted on said carriage in a position to cut the webs along a transverse axis and to lie very near the bite point when the carriage reaches the end of its travel toward the rollers, a latch means pivotally mounted on said carriage and disposed to engage one of said racks to hold the carriage in a fixed position when the carriage has reached the end of its travel toward the rollers, a shaft parallel to said rollers journaled in said carriage and carrying resilient rollers spaced from each other along said shaft centrally opposite the collocating sections and adjustably disposed to hold the slit webs against the periphery of the collocating sections when the webs are presented to the bite, the shaft adapted to be overdriven, drives the resilient rollers in a manner that each slit web will be tautly driven into the bite, a means operable for driving said parallel shaft through a predetermined number of degrees rotation after the carriage has reached the end of its travel toward the rollers, a means pivotally mounted on one of the racks for disengaging the latch means from the rack, and a means carried by said driving means for actuating the means to disengage the latch means from the rack after the webs have been driven into the bite.

10. In an apparatus for cutting and coiling a web of paper comprising a pair of rollers having parallel axes located at different levels, rotatable in opposite directions and disposed to form a bite, a pair of longitudinally spaced parallel externally supported racks extending rearwardly from a point proximate to the bite, the racks being fixed with respect to one of said rollers, a carriage supported by said racks and movable thereon toward and away from said rollers, the movement of the carriage being of a distance so that the web of paper passing between the rollers partially around one of the rollers and over the carriage will be severed along a transverse axis and the cut edge remaining will be presented to the bite when the carriage terminates its travel toward the rollers, a means carried by said carriage for limiting movement of the carriage toward the rollers by one of the rollers, a stop means mounted on one of said racks for limiting movement of the carriage away from the rollers, a means for constantly urging the carriage away from said rollers, thereby normally holding the carriage against the stop means, a cutting means mounted on said carriage in a position to cut the web along a transverse axis and to lie very near the bite point when the carriage reaches the end of its travel toward the rollers, a latch means pivotally mounted on said carriage and disposed to engage one of said racks to hold the carriage in a fixed position when the carriage has reached the end of its travel toward the rollers, a shaft parallel to said rollers journaled in said carriage and carrying a resilient roller disposed to hold said web of paper against the periphery of one of said rollers when the web is presented to the bite, a means for driving said parallel shaft through a predetermined number of degrees rotation after the carriage has reached the end of its travel toward the rollers, a means operable pivotally mounted on one of the racks for disengaging the latch means from the rack and a means carried by said driving means for actuating the means to disengage the latch means from the rack after the webs have been driven into the bite.

11. In an apparatus for cutting and coiling slit paper webs comprising a pair of rollers having parallel axes located at different levels, rotatable in opposite directions and disposed to form a bite, one of the rollers being composed of a plurality of collocating sections, thereby providing separate cores for slit paper webs to be wound on each section, the other roller being unitary in construction, a pair of longitudinally spaced parallel racks extending rearwardly from a point proximate to the bite, the racks being fixed with respect to the roller of unitary construction, one of said racks being provided with a shoulder portion, a carriage movable on said racks toward and away from said rollers, the length of carriage travel being of a distance so that the slit webs passing between the rollers partially around the collocating sections and over the carriage will be severed along a transverse axis and the cut edge remaining will be presented to the bite at the end of travel of the carriage toward the rollers, a suitable means carried by said carriage for limiting movement of the carriage toward the rollers by the roller of unitary construction, a stop means mounted on one of said racks for limiting movement of the carriage away from said rollers, a means for constantly urging the carriage away from said rollers, thereby normally holding the carriage against said stop means, a cutting means mounted on said carriage in a position to cut the webs along a transverse axis and to be very near the bite point when the carriage reaches the end of its travel toward the rollers, a latch means pivotally mounted on said carriage and disposed to engage the shoulder portion of one of said racks to hold the carriage in a fixed position when the carriage has reached the end of its travel toward the rollers, a shaft parallel to said rollers journaled in said carriage and carrying resilient rollers spaced from each other along said shaft centrally opposite the collocating sections and disposed to hold the slit webs

against the periphery of the collocating sections when the webs are presented to the bite, the shaft adapted to be driven drives the resilient rollers, thereby driving said webs into the bite, a means operable for driving said parallel shaft through a predetermined number of degrees rotation after the carriage has reached the end of its travel toward the rollers, a means operable pivotally mounted on one of said racks for disengaging the latch means from the shoulder portion of said rack, and a means carried by said driving means for actuating the means to disengage the latch means from the shoulder portion of said rack upon the webs being driven into the bite.

15. In an apparatus for cutting and coiling slit paper webs comprising a pair of rollers having parallel axes located at different levels, rotatable in opposite directions and disposed to form a bite, one of the rollers being composed of a plurality of collocating sections, thereby providing separate cores for slit paper webs to be wound on each section, the other roller being unitary in construction, a pair of longitudinally spaced parallel externally supported racks extending rearwardly from a point proximate to the bite, the racks being fixed with respect to the roller of unitary construction, one of said racks 20 having a shoulder portion provided therein, a first rotatable shaft parallel to said rollers and fixedly carrying a pinion gear on each end disposed to engage said racks, a carriage rotatably supporting said parallel shaft so as to be movable on said racks toward and away from said rollers, the length of carriage travel being of a distance so that the slit paper webs passing between the rollers, partially around the collocating sections and over the carriage will be severed along a transverse axis and the cut edge remaining will be presented to the bite at the end of travel of the carriage toward the rollers, a means carried by said carriage for maintaining said pinion gears in engagement with said racks and thereby supporting said carriage on said racks, a means carried by said carriage for limiting movement of the carriage toward the rollers 25 by the roller of unitary construction, a stop means mounted on one of said racks for limiting movement of the carriage away from said rollers, a means for constantly urging the carriage away from said rollers, thereby normally holding the carriage against the stop means, a cutting means having a plurality of upwardly curved V-shaped teeth mounted on said carriage in a position to cut the web along a transverse axis and to lie very near the bite point when the carriage reaches the end of its travel toward the rollers, a retractable guard positioned to normally cover said cutting means and provided with a plurality of slots, a means operable for retracting said guard to expose said cutting means as the carriage is moved toward the rollers, a means operable for retaining said guard to cover said cutting means as the carriage 30 is moved away from said rollers, a plurality of guide pins fixed to said carriage and located within the slots of said guard to guide the movement thereof, a latch means pivotally mounted on said carriage and disposed to engage said shoulder portion provided in one of said racks, a second rotatable shaft parallel to said rollers journaled in said carriage and rotatably carrying resilient rollers spaced from each other along said shaft centrally opposite the collocating sections and disposed to hold the slit webs against the periphery of the collocating sections 35 when the webs are presented to the bite, the shaft adapted to be driven drives the resilient rollers, thereby driving said webs into the bite, a means operable for driving said second parallel shaft through a predetermined number of degrees rotation after the carriage has reached the end of its travel toward the rollers, a means operable pivotally mounted on one of said racks for disengaging the latch means from the shoulder portion provided in said rack, and a means carried by said driving means for actuating the means for disengaging the latch means 40

from said shoulder portion after the webs have been driven into the bite.

13. In apparatus for cutting and coiling of a web of paper comprising: a pair of rollers having parallel axes located at different levels, disposed to form a bite and rotatable in opposite directions, a cutting means movable toward and away from said rollers, the length of travel of said cutting means being of a distance so that the web of paper passing between the rollers and partially around one of the rollers and over the cutting means will be severed along a transverse axis and the cut edge remaining will be presented to the bite when the cutting means terminates its travel toward the rollers, means for holding the transversely cut web of paper against the periphery of one of said rollers when the web is presented to the bite, and means for overdriving said web so that any slack occurring will be taken up as the web is driven into the bite.

14. In an apparatus for cutting and coiling a web of paper, a pair of rollers having parallel axes located at different levels disposed to form a bite and rotatable in opposite directions; a cutting means movable toward and away from said rollers, the length of travel of said cutting means being of a distance so that the web of paper passing between the rollers and partially around one of the

10
15

rollers and over the cutting means will be severed along a transverse axis and the cut edge remaining will be presented to the bite as the cutting means terminates its travel toward the rollers; retractable holding means for holding the end of the transversely cut web of paper against the periphery of one of said rollers when the web is presented to the bite, said holding means being capable of driving said web into the bite; means for actuating said holding means to drive said web into the bite; and means for retracting said retractable holding means upon the same driving said web into the bite.

15. In an apparatus for cutting and coiling a web of paper as in claim 14 wherein said means for actuating said retractable holding means is driven by one roller of said pair of rollers.
